Primary Examiner — Cary M Robinson*Assistant Examiner* — Emily Anna Saunders(57) **CLAIM**

The ornamental design for an educational toy, as shown and described.

DESCRIPTION

FIG. 1 is a front, right, bottom perspective view of the educational toy, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines in the figures are for the purpose of illustrating portions of the educational toy and form no part of the claimed design.

1 Claim, 7 Drawing Sheets(56)
